The ornamental design for a six-step snow-making gun, as shown and described.

DESCRIPTION

This design application is related to contemporaneously filed design patent application titled: Four-Step Snow-Making Gun, bearing Ser. No. 29/430,678, and contemporaneously filed design application titled: Single-Step Snow-Making Gun, bearing Ser. No. 29/430,679.

FIG. 1 is a left-side view of a six-step snow-making gun showing my new design;

FIG. 2 is a front view thereof;

FIG. 3 is a right-side view thereof;

FIG. 4 is a rear view thereof;

FIG. 5 is a top view thereof;

FIG. 6 is a bottom view thereof;

FIG. 7 is a rear perspective view thereof; and,

FIG. 8 is a front perspective view thereof.
